(57) **CLAIM**

The ornamental design for a sensor housing of an agricultural work vehicle, substantially as shown and described.

DESCRIPTION

FIG. 1 is a perspective view of a sensor housing of an agricultural work vehicle;

FIG. 2 is a perspective view of the sensor housing;

FIG. 3 is a left side view of the sensor housing, the right side view being a mirror image of the left side view being shown;

FIG. 4 is a top view of the sensor housing;

FIG. 5 is a front view of the sensor housing;

FIG. 6 is a back view of the sensor housing; and,

FIG. 7 is a bottom view of the sensor housing.

Phantom lines, where utilized, are for illustrative purposes only and form no part of the claimed design.

1 Claim, 4 Drawing Sheets
